UNITED STATES PATENT OFFICE.

CHRISTIAN EITLE, OF STUTTGART, GERMANY.

GAS-RETORT-FEEDING MACHINE.

No. 903,184.

Specification of Letters Patent. Patented Nov. 10, 1908.

Application filed September 13, 1904. Serial No. 224,240.

To all whom it may concern:

Be it known that I, CHRISTIAN EITLE, a subject of the German Emperor, residing at Stuttgart, Germany, have invented a certain new and useful Gas-Retort-Feeding Machine, of which the following is a specification.

This invention relates to an improved gas retort feeding machine of the type in which the feeding of the retorts is effected by means of a centrifugal drum, the material being supplied to the drum by inclined passages or channels connected to both sides of the drum as described in my application, Serial No. 177,860, filed October 21, 1903, Patent No. 793,773, of July 4, 1905.

When in charging retorts coal is used consisting of pieces of different size and of coal screenings, the speed of travel of the material in the passages and also the speed at which it enters into the retorts, depends of course upon the sizes and differs in accordance therewith so that the charging process is not uniform. Owing to the feeding of the coal to the centrifugal wings at both sides of the drum, the pieces of coal show a tendency to accumulate in the center of the retort over its entire length, so that the cross section is largest in the middle. This accumulation is a serious disadvantage, as owing to same the heating surface of the retort is not sufficiently utilized and part of the gasification is only effected by radiation from the walls not in contact with the material. Moreover owing to the condensed moisture in the retort-heads, dust will accumulate and combine with the water, tar, etc. collected there and thus in a short time interfere with the free supply of coal and interfere with the charging operation. Furthermore it has not been found advantageous completely to close the retort during the charging process by means of the ejecting nozzle and covering plate connected thereto, inasmuch as the formation of gas during the charging is sudden and excessive, so that the gas cannot be carried off through the pipes. These drawbacks are overcome by my improved apparatus hereinafter described and illustrated in the annexed drawing, forming a part of the specification, and in which:—

Figure 1 is a view of such device applied to a retort taken in central vertical longitudinal section. Fig. 2 is a top view thereof taken in section on the line y—y of Fig. 1.

Fig. 3 is a view of a portion of the device as shown in Fig. 1, the feeding-chute being shown in full lines raised into the position shown in dotted lines in Fig. 1, to permit of shifting the device to another position. Fig. 4 is a rear view of the feed-hopper etc. in vertical section on the line z—z of Fig. 2 and Fig. 5 is an end view of the feed-chute, taken in cross section.

The centrifugal wings, of which there may be two, three or any suitable number are provided at their rear side with segmental side walls c, c, which during their rotation partly cover the feed openings of the lateral channels or passages like slides, so as to prevent the feeding of the material; the quantity of the material fed depending upon the size of these lateral walls or partitions.

The bottom a of the discharge channel, the front part d of which may be swung around and upwards on a hinge, is shaped like a slide and is provided with a wedge shaped piece b. The side walls f f of the discharge channel are also extended up to the mouth of the retort.

The manner of operating the device is as follows: The bottom slide a is pushed forward into the head of the retort, after the discharge channel d has been swung around in the direction of the retort, so that the bottom surface of the head of the retort is covered; then the centrifugal wings are rotated, and the coal is admitted to the wings from both sides through the inclined channels h h and from the measuring vessel i by withdrawing a slide k, the coal being then thrown by the wings across the slide into the retort. By means of the wedge-shaped piece b the stream of material is divided, so that it is deflected from the center line and is thrown to both sides whereby the coal is caused to become deposited in a trough like manner on both sides, so as to have the coal cover a larger heating surface, as illustrated in cross section in Fig. 5. The space between the discharge channel and the head of the retort is thus closed on three sides, so that the gases and the flames can only escape in an upward direction without causing any inconvenience or danger to the operating crew. After the feeding has been finished, the bottom slide is withdrawn and the discharge hopper d is swung upwards as shown in dotted lines in Fig. 1 and also in Fig. 4. In this position the lower part of the bottom slide a will deflect and balk the air cur-

rent caused by the movement of the wings of the centrifugal apparatus so as to prevent the same from entering the retort, so as to avoid the cooling of the hot retorts, as well as losses of gas and explosion.

5 The apparatus is arranged like a crane or derrick upon a truck or small car movable in front of the furnaces and so as to be vertically displaceable in accordance with the 10 position of the retorts. This arrangement is clearly shown in Fig. 1 and is so well known in mechanics, that no further description is deemed necessary.

What I claim and desire to secure by Letters Patent of the United States is:—

15 1. In a machine for feeding gas retorts, a centrifugal feeding device, a feed-chute, means for forming a tight joint between the walls of the exit of the feed-chute and the

retort-mouth, a movable bottom piece for 20 such feed-chute at the exit end and means secured to such bottom piece adapted to insure a uniform distribution of the coal in the retort.

2. In a machine for feeding gas-retorts, a 25 centrifugal feeding device, a feed-chute, lateral walls adapted to form a tight joint between the walls of the exit of the feed-chute and the retort mouth, a movable bottom piece for such feed chute at the exit end and a wedge-shaped piece secured to said bottom piece.

In witness whereof I have hereunto set my hand in presence of two witnesses.

CHRISTIAN EITLE.
